(No Model.)

L. JOHNSTON.

2 Sheets—Sheet 1.

COMBINED TOILET CASE AND SATCHEL.

No. 312,355.

Patented Feb. 17, 1885.

FIG. 1.

FIG. 2.

FIG. 3.

WITNESSES

B. C. Fenwick
J. P. Thos. Lang.

INVENTOR

Louella Johnston
Fenwick and Lawrence

Attorneys

(No Model.)

2 Sheets—Sheet 2.

L. JOHNSTON.

COMBINED TOILET CASE AND SATCHEL.

No. 312,355.

Patented Feb. 17, 1885.

FIG 4.

WITNESSES:

B. C. Fornescher
J. D. Theo. Lang.

INVENTOR:

Louella Johnston
by
Henry K. Lawrence

Attorneys

UNITED STATES PATENT OFFICE.

LOUELLA JOHNSTON, OF COLUMBUS, OHIO.

COMBINED TOILET-CASE AND SATCHEL.

SPECIFICATION forming part of Letters Patent No. 312,355, dated February 17, 1885.

Application filed December 26, 1884. (No model.)

To all whom it may concern:

Be it known that I, LOUELLA JOHNSTON, a citizen of the United States, residing at Columbus, in the county of Franklin and State of Ohio, have invented a new and useful Improvement in Portable Combined Toilet-Case and Satchel or Reticule, of which the following is a specification.

The invention which I have made is intended to supply a want long felt by ladies traveling, by providing a ready and conveniently accessible combined toilet-case and satchel, which, while answering as a small hand satchel or reticule for containing comb, brush, and small parcels, serves also for supporting and concealing a toilet or looking glass, box for containing face or cooling powder, perfumery, glycerine, or other cosmetics, either of which articles can be reached or brought into use by simply unfastening an ornamental rosette-shaped flap or cover and turning the same down on its lower connection with the material forming the main pocket of the satchel or reticule.

In the accompanying drawings, Figure 1 is a side view of my improved combined toilet-case and satchel as it appears when its side flaps are closed; Fig. 2, a similar view with one of the side flaps unfastened and turned down to expose the cosmetics. In this view one of the bottles is shown partly out of its pocket. Fig. 3 is a similar view showing the flap which covers the toilet or looking glass unfastened and turned down, and Fig. 4 is a vertical cross-section in the line xx of Fig. 1.

The toilet-case comprises as a foundation an inside lining, A, of leather, which forms a main pocket, a, of a satchel, and on the two inner sides of this pocket small receptacles b and c are formed, one serving for a comb and the other for a brush; or the pocket a and receptacles b and c may be used for any small articles required by ladies while traveling. The portion A is constructed in all respects similar to an ordinary hand-satchel with entrance or mouth and fastening of the usual kind. This lining is covered with cloth, velvet, or other flexible finishing material, B, wrought into the form or design represented, or in any other suitable form and design. Near the center of each side of this outside finishing material a circular or other shaped opening is made, and back of each of these openings a stiff pasteboard, leather, or other stiff support, as d or d', is applied, and the cloth 55 or velvet securely glued, sewed, or otherwise suitably fastened to the same. Near the edge of the pasteboard d a circular bead, of india-rubber or other flexible substance, as f, covered with plush, cloth, or velvet, is placed 60 and securely confined. This bead, with the pasteboard d, forms a circular or oval frame for a toilet-glass, g, and by pressing aside the bead with the fingers the glass g can be placed against the pasteboard, and when so placed, 65 and the bead is allowed to assume its normal condition, it will be held securely in position. If the glass should be accidentally broken, it can be removed by pressing aside the bead and another readily introduced in its place. Over 70 this looking-glass an ornamental rosette or cover, h, is applied, it being secured near its lowest part by rivets, thread, or otherwise to the finishing material of the combined toilet-case and satchel, and provided with a fastening-loop, p, at its highest portion, as shown. By detaching the fastening-loop from its button p' the rosette can be turned so as to expose the toilet or looking glass for use, as illustrated in Fig. 3. When the rosette is fastened 75 by its loop and button, the glass is completely concealed. In using the glass the owner of the toilet-case and satchel can place the toilet-case and satchel with the rosette lowered in front of her face, and no person will know that 80 the glass is being utilized, and this will be a satisfaction to sensitive ladies, who desire privately to examine their appearance while at opera, theater, or traveling in cars or other vehicles, or under other circumstances. On 85 the other side of the finishing covering, and on the pasteboard support d', small pockets m n are provided for the reception of perfumery and glycerine bottles, as shown, and between these pockets a box, n', for face-powder is secured by glue or in any other suitable manner, 90 as shown, and over these pockets and the box a rosette, h', exactly similar in form, arrangement, and operation to the rosette which is placed over the toilet or looking glass, is applied, as shown. This rosette h' conceals from 95 view the pockets, bottles, and powder-box, 100 and by lowering the rosette, as illustrated in Fig. 2, access is secured to either of the desired cosmetics.

My combined toilet-case and satchel can be made very ornamental, and it will be found a very useful, convenient, and desirable article for ladies, who are necessarily exposed in traveling to the gaze of all about them while making their toilet or using the looking-glass while applying cosmetics.

What I claim as my invention, and desire to secure by Letters Patent, is—

1. The improved article of manufacture—viz., a combined toilet-case and satchel comprising suitable inside pockets, outside receptacle or frame for a toilet or looking glass on a stiff support, the outer flexible finishing material, and a flap-cover for the said glass, substantially as described.

2. The improved article of manufacture—viz., a combined toilet-case and satchel comprising suitable inside pockets, outside receptacles for cosmetics on a stiff support fastened to the outer finishing material, and a flap-cover for the said receptacles, substantially as described.

3. The improved article of manufacture consisting of the combined toilet-case and satchel, the same having suitable inside pockets, outside frame, and suitable supports on the outside flexible finishing material for a toilet or looking glass, receptacles for cosmetics, and flap-covers for the glass and cosmetics, substantially as described.

LOUELLA JOHNSTON.

Witnesses:

J. Q. A. ROBINSON,
A. H. FRITCHLEY.